W. C. WEEKS.

EXCAVATING DEVICE.

APPLICATION FILED FEB. 19, 1913.

1,110,604.

Patented Sept. 15, 1914.

UNITED STATES PATENT OFFICE.

WILLIAM C. WEEKS, OF VANCOUVER, BRITISH COLUMBIA, CANADA.

EXCAVATING DEVICE.

1,110,604.

Specification of Letters Patent. Patented Sept. 15, 1914.

Application filed February 19, 1913. Serial No. 749,544.

To all whom it may concern:

Be it known that I, WILLIAM C. WEEKS, a citizen of the United States, and resident of the city of Vancouver, Province of British Columbia, Canada, have invented certain new and useful Improvements in Excavating Devices, of which the following is a specification.

My invention relates to excavating devices, particularly of that type which employs a drag bucket as the excavating and transporting member.

The object of my invention is to better adapt such devices to certain special uses and to improve the same generally.

My invention comprises the novel parts and combinations of parts which are herein-after described and particularly pointed out in the claims.

20 In the accompanying drawings I have shown my invention in the form which is now preferred by me.

Figure 1 is an elevation showing a side view of an apparatus made in accordance 25 with my invention. Fig. 2 is a detail showing, in side elevation, the carriage and its mechanism whereby it may be locked to the trackway and whereby the drag bucket may be locked to and released therefrom.

30 The apparatus which is the subject of my invention has been more particularly designed for dredging from a scow or float, but it is evident that it may be used for other purposes and under other conditions; 35 particularly may it be used to advantage to excavate from beneath a platform which is supported in an elevated position.

The platform upon which the operating machinery is supported is, as illustrated, a 40 scow, 1. This float has spars or frames extending outboard, or beyond its ends, at opposite ends, these serving as supports for the guides through which the main-haul line and the back-haul lines pass. At one end, 45 the spar or frame 61, supports the pulley 62, outward from the end of the float, said pulley serving as a guide for the back-haul rope 6. This back-haul line extends to and is operated by a drum 60, upon the float. At 50 the other end of the float, a spar or frame 8, extends outward and serves as the support for the lower end of an inclined trackway, represented by the beam 2. The upper end of this trackway is supported over this end 55 of the float, as by a mast or frame work represented by the post 10. The inclined

trackway 2, should preferably extend from a point near the water level upwardly and inwardly over the end of the float, so that the excavating bucket may travel up thereon, into position where it may be dumped into a hopper, chute, or other receptacle, herein represented by the hopper 7. The location of the trackway should be such that the bucket will clear the end of the float and the hopper 7. The bucket 4 may be of any type which may be found suitable for working with the rest of the apparatus. The bucket herein shown is of an old type. The haul-back line 6 is connected thereto and extends beneath the float. It is therefore capable of drawing the bucket back beneath the float, so that its loading travel may be substantially the length of the float, or the distance between the line guides at each end 75 of the float. The trackway beam 2, has, running thereon, a carriage 3, which has thereon a guide wheel 30, about which passes the main-haul line 5, to a connection with the bail 40 of the bucket 4. The lower end 80 of the trackway has a catch lever 33, pivoted thereto at 20, the end opposite the pivot being shaped to form a hook or dog, having its outer, lower surface inclined, so that a pin or lug 31, carried by the carriage, will engage said catch lever, or dog, to raise it, whereupon the catch will engage and hold the carriage against returning up the trackway, until this catch has been released. A lever 32 is pivoted upon the carriage and 85 has an arm 38, in position to engage the catch dog 33, to disengage it from the pin 31 when lever 32 is raised, thus freeing the carriage so that it may travel up the trackway. The carriage also has an arm or finger 34, 90 depending therefrom and having its lower end 37, curved and serving as a guide for the bail of the bucket, when it is hoisted thereto. The lower portion of this arm 34, has a catch dog, or lever 35, pivoted thereto 95 and held against dropping down by a stop 36 upon the arm 34. The main-haul line 5, extends from an engine drum 50, over a guide pulley 51 at the upper end of the inclined trackway and then about the pulley 100 105 30 upon the carriage.

In operating this device, the bail of the bucket will be presumed as resting upon and supported by the catch dog 33, being held thereby against sinking away from the carriage. If the main-haul line be permitted to run out, the carriage will descend the in-

clined trackway until it is caught and held against return by the catch dog 33. In this position, a pull upon the haul-back line will pull the bail of the bucket off of the catch 35 and permit drawing the bucket back under the float, to a point under the pulley 62. After the bucket has been dropped at the rear end of the float, the main-haul line is pulled in, drawing the bucket forward and filling it. The carriage, during this time, is locked to the lower end of the inclined trackway. When the bucket is raised, the bail 40 contacts with the catch 35, raising it out of the way, but permitting this catch to drop down into holding position as soon as the bail has passed. The further progress of the bucket bail, will engage the releasing lever 32 and free the carriage from the dog 33, whereupon, the pull upon the line 5 will start the carriage up the inclined trackway. This permits the bucket to drop, but, as the catch 35 is beneath the bail, the bucket is held by this catch and rises with the carriage. When the bucket gets over the hopper 7, or whatever other receiving member is used, the bucket is dumped and then the carriage and the bucket suspended therefrom, runs down the inclined trackway until engaged by the catch 33. By extending the spars or frames, 8 and 61, outward a considerable distance, it is possible to dredge over a distance much greater than the length of the float. It is evident that the device herein described may be used on dry land by providing means for supporting the platform which carries the machinery, above the material to be excavated.

What I claim as my invention is:

1. An excavating device comprising an elevated machinery-supporting platform, a drag bucket, a main-haul line attached to the bucket, a back-haul line also attached to the bucket, a guide for the back-haul line located at one end of the platform to lead the back-haul line beneath the platform, a guide for the main-haul line located beyond the other end of the platform, and means for moving said latter guide upward and inward over that end of the platform.
2. An excavating device comprising a float having a projecting guide-supporting member at each end, a drag bucket, a main-haul line secured to the bucket, a back-haul line also secured to the bucket, a guide for the back-haul line carried by said projecting member at one end of the float, a guide for the main-haul line and means for supporting the said guide from said projecting member at the other end of the platform, to move said guide in an inclined path over the end of said platform.

3. An excavating device comprising a float, a drag bucket, a main-haul line, a back-haul line, guides for said lines supported from and beyond opposite ends of the float and adjacent the water line and means for shifting the guide for the main-haul line upward and inward to a point over the float.

4. An excavating device comprising a float, a drag bucket, a main-haul line, a back-haul line, a guide for the back-haul line located to lead the said line beneath the float, an inclined trackway having its lower end extending beyond the other end of the float, a carriage adapted to travel upon said trackway, and a guide for the main-haul line supported upon said carriage.

5. An excavating device comprising a float, a drag bucket, a main-haul line, a back-haul line, means for conducting the back-haul line beneath one end of the float, an inclined trackway having its lower end beyond the other end of the float and its upper end above the float, a fixed guide for the main-haul line at the upper end of the trackway, a carriage movable along the trackway and carrying a guide for the main-haul line, and means for locking the carriage to the lower end of the trackway when desired.

6. An excavating device comprising a float, a drag bucket, a main-haul line, a back-haul line, means for conducting the back-haul line beneath one end of the float, an inclined trackway having its upper end over one end of the float and its lower end beyond that end of the float, a guide for the main-haul line at the upper end of the trackway, a carriage running upon the trackway, a guide for the main-haul line carried upon the carriage, means controlled by the bucket under the action of the main-haul line for locking the carriage at the lower end of the trackway and for releasing the carriage.

7. An excavating device comprising a float, a drag bucket, a main-haul line, a back-haul line, means for conducting the back-haul line beneath one end of the float, a guide for the main-haul line and means for moving said guide for the main-haul line in a path extending from a point outboard of the other end of the float to a point over the same end of the float.

In testimony whereof I have hereunto affixed my signature, at Vancouver, British Columbia, this 12 day of February, 1913.

WILLIAM C. WEEKS.
